(57) **CLAIM**

The ornamental design for a vapor proof LED fixture, as shown and described.

DESCRIPTION

FIG. 1 is a perspective view of an embodiment of the new design;

FIG. 2 is a front view of the embodiment;

FIG. 3 is a right view of the embodiment;

FIG. 4 is a left view of the embodiment;

FIG. 5 is a rear view of the embodiment;

FIG. 6 is a top view of the embodiment;

FIG. 7 is a bottom of the embodiment; and,

FIG. 8 is the perspective view of the embodiment of FIG. 1 with the cage removed.

The design consists of the features of shape, ornament and configuration of the article shown in the drawings. The broken lines shown in the drawings are for the purpose of illustrating portions of the article that form no part of the claimed design.
